COMBINED SURVEILLANCE CAMERA SUPPORT AND ACTUATOR UNIT

Norman M. Kiven, 814 W. Diversey Parkway,
Chicago, Ill. 60614

Filed Aug. 21, 1968, Ser. No. 13,227

Term of patent 14 years

Int. Cl. D16—07

U.S. Cl. D61—1

FIG.1

FIG.2

FIG.3

FIG.4

FIG.5

FIG.6

FIGURE 1 is a pictorial view of the inventive unit;
 FIGURE 2 is a top view of the inventive unit;
 FIGURE 3 is a side view;
 FIGURE 4 is a front view;
 FIGURE 5 is a back view; and
 FIGURE 6 is a bottom view.

The mounting bracket, receptacles, electric cord, screw heads, and camera mounting pin shown in broken lines are for illustrative purposes only; the essential features of my design reside in those portions shown in full lines.

I claim:

The ornamental design for a combined surveillance

camera support and actuator unit, as shown and described.
